Fig. 4

FIGURE 1 is a front elevational view of a combined cover and pushbutton operators for an enclosing case of an electrical controller, showing our new design;

FIG. 2 is a view in longitudinal cross section taken on the line 2—2 of FIG. 1;

FIG. 3 is a view in transverse cross section taken on line 3—3 of FIG. 1;

FIG. 4 is another transverse cross sectional view taken on the line 4—4 of FIG. 1; and

FIG. 5 is a perspective view of the combined cover and pushbutton operators for enclosing case for an electrical controller shown in FIGS. 1 to 4.

The dominant features of our new design reside in the portions shown in solid black lines in the drawings.

Portions shown in broken lines are for purposes of illustration only.

We claim:

The ornamental design for a combined cover and pushbutton operators for an enclosing case of an electrical controller, substantially as shown and described.
